UNITED STATES PATENT OFFICE

MEYER REINGOLD, OF BROOKLYN, NEW YORK

CONCEALABLE RUNNING BOARD LUGGAGE CARRIER

Application filed August 12, 1930. Serial No. 474,818.

The invention relates to a luggage carrier which may be used advantageously in conjunction with the running boards or similar parts of automobiles.

5 The invention contemplates a luggage carrier of the indicated character which will be permanently applied to a running board or the like platform, so as to be conveniently accessible at all times, and which may be readily set up for use, and which when not in use may be safely concealed from view ready for use whenever the occasion arises.

10 With the foregoing and other objects in view, the invention resides in the combination, construction and functions of the parts hereinafter described and illustrated in the accompanying drawings, in which:

15 Figure 1 is a perspective view illustrating the device applied to an automobile, a portion of which is shown;

20 Figure 2 is a view similar to Figure 1 but showing the device ready for use;

25 Figure 3 is a section on the line 3—3 of Figure 1, the carrier frame being shown in the concealed position in relation to the running board;

30 Figure 4 is a view similar to Figure 3, but showing the carrier frame drawn out;

35 Figure 5 is an enlarged section on the line 5—5 of Figure 2;

40 Figure 6 is a fragmentary perspective sectional view showing certain features of the device.

45 Referring now more particularly to the drawings, it will be apparent that there is shown by way of example a portion of an automobile 10, and one of its running boards 11. A plate 12 substantially equal in length and width to the running board 11 is secured in place in any suitable manner underneath the running board in spaced relation with respect thereto, and said plate along its ends and one side or longitudinal edge being provided with upstanding flanges 13 which contact with the under surface of the running board 11. It will therefore be apparent that the running board 11 together with the plate 12 constitute a housing having an opening 14 located along the outside of the running board 11. A luggage carrier retaining frame

15 is permanently connected in relation to the running board 11 so as to be moved from a concealed position in the housing to an upstanding position along the outer longitudinal edge of the running board, constituting a 55 luggage carrier in conjunction with the running board 11, and adjoining parts of the automobile. The frame 15 is substantially of rectangular formation in the present instance and consists of longitudinal members connected together by transverse members, all of which are made preferably of strips of metal. The frame 15 may be of any preferred length and in the present instance is equal to the length of the running board 11. 60 65

For permanently connecting the frame 15 in relation to the running board 11 so that it may be moved to the position mentioned hereinabove, there is provided means presently to be described which may be diversely formulated. The said means includes linkage at each end of the running board consisting of pairs of link members 16 and 17 pivotally connected together, as at 18, the link member 16 being pivotally connected, as at 19, with the plate 12, and the link member 17 being pivotally connected with a hinge 20 on the related lower edge end of the frame 15. The provision of the link members 16 and 17 at each end of the frame 15 together 70 75 80 with the hinged connection 20 makes it possible to move the frame 15 into the housing provided by the running board 11 and the plate 12 through the opening 14, as shown in Figure 3, and also makes it possible to move the frame 15 exteriorly of the constituted housing to a position in which it will be disposed substantially perpendicular to the running board 11 with the lower edge of the frame at the outer edge of the running board, as 85 90 shown in Figures 2 and 5. The link members 16 and 17 rest on the plate 12 so that the frame 15 will be firmly supported in the perpendicular upstanding position.

95 Any practical means may be provided for releasably retaining the frame 15 in its upstanding position. In the present instance, the plate 12 is provided with a longitudinal slot 21 along the outer edge thereof, which may be formed in the plate 12 or which may 100

be formed by applying a strip of metal 22 along the outer edge of the plate 12, as shown in the present instance. Brace members 23 in the form of metal bars are each pivotally connected at one end with the frame 15 as at 24, and the lower end thereof is receivable in the slot 21, in frictional engagement with the adjacent faces of the plate 12 and the strip 22. These members 23 may be swung on their 10 pivots into the slot 21 to releasably retain the frame 15 in the upstanding position, or may be swung out of the slot 21 in order that the frame 15 may be moved through the opening 14 into the housing constituted or formed 15 by the running board 11 and the plate 12. When the members 23 are released, the frame 15 may be swung from the vertical to the horizontal position, whereupon it may be pushed into the housing, and the members 16 20 and 17 incidentally moving on their pivotal connections.

In order to close the opening 14 when the frame 15 is moved into the constituted housing, there is provided a closure member 25 25 hingedly connected along one edge, as at 26, with the outer side edge of the running board 11. The closure member 25 may be swung to an upstanding position when the frame 15 is to be moved and held in the up- 30 standing position, as shown in Figure 5. The closure member 25 serves to fully close the opening 14 to exclude dust and dirt.

It is to be understood that the invention is not restricted to the precise arrangement of 35 parts shown and described, as details of construction may be modified and rearranged without departing from the spirit of the invention, the scope of which is limited only by the terms of the appended claims.

40 What is claimed is:

1. The combination of a vehicle running board, a plate secured to the underside of the running board in spaced relation and presenting a side opening, a linkage pivotally connected with and resting on said plate, a carrier frame pivotally connected with said linkage, whereby said frame may be moved into position between the running board and plate through said opening and from the said 45 position to a position substantially perpendicular to the running board with the lower edge abutting the latter, and means to retain the frame in the second mentioned position.

2. The combination of a vehicle running board, a luggage retaining frame connected in relation to the running board for movement from a position beneath the running board to an upstanding position in relation to the outer edge of the running board, and 55 means to releasably retain the frame in the upstanding position, said means consisting of brace members carried by said frame, and a slotted section connected with the running board to receive the lower ends of said brace members respectively.

3. The combination of a vehicle running board, a plate secured to the underside of the running board in spaced relation and presenting a side opening, a carrier frame, pivotally connected link members pivotally connected with and resting on said plate for each end of said carrier frame, means pivotally connecting the lower edge of said carrier frame at each end with the related link members, whereby said frame may be moved into position between the running board and plate through said opening and from the said position to a position substantially perpendicular to the running board with the lower edge abutting the latter, and means to retain the frame in the second mentioned position.

4. The combination of a vehicle running board, a plate secured to the underside of the running board in spaced relation and presenting a side opening, a linkage pivotally connected with said plate, a carrier frame pivotally connected with said linkage, whereby said frame may be moved into position between the running board and plate through said opening and from the said position to a position substantially perpendicular to the running board with the lower edge abutting the latter, and means to retain the frame in the second mentioned position, said last means consisting of brace members carried by said frame and slotted sections embodied in said plate to receive the lower ends of said brace members respectively.

Signed at New York, in the county of New York and State of New York, this 11th day of August A. D. 1930.

100 MEYER REINGOLD.
